UNITED STATES PATENT OFFICE.

JOHN J. HOGAN, OF BRIDGEPORT, CONNECTICUT.

GAS-ENGINE.

1,253,599.

Specification of Letters Patent. Patented Jan. 15, 1918.

Application filed April 14, 1918. Serial No. 91,058.

To all whom it may concern:

Be it known that I, JOHN J. HOGAN, a citizen of the United States, residing at Bridgeport, Connecticut, have invented certain new and useful Improvements in Gas-Engines, of which the following is a clear, full, and exact description.

This invention relates to hydrocarbon engines of the so called two-cycle type. 10 Broadly speaking, my main object is to simplify the structure and to incorporate improved features of construction with a view to attaining high efficiency.

In engines of the two-cycle variety great difficulty is found in fully charging the working cylinder with an effective mixture of air and fuel. This is due to various causes, but is commonly due to the fact that the entire charge is ordinarily introduced in 20 a very short period of time represented by only a small fraction of the movement of the piston. This not only has made it impossible to introduce a charge which in volume is at least equal to the displacement 25 of the piston throughout its full stroke, but has made it physically impossible to introduce into the combustion chamber a volume actually greater than the piston displacement. By my improvement, I am able to 30 introduce into the working cylinder a charge of practically any desired volume as will later be seen by reference to the drawings and a reading of the specification. As a result of my improvement I am able to successfully use fuel that would otherwise not be available for use in engines of the two-cycle variety. This is due to the fact that I can so proportion the parts as to secure 35 any desired degree of compression within 40 reason. I also attain a materially higher efficiency than heretofore attained in such engines, and these ends I accomplish by the use of a very few parts of very simple construction, but new in their arrangement and 45 combination.

In the accompanying drawings:

Figure 1 is a vertical section of a one cylinder engine embodying my invention.

Fig. 2 is a cross section on the line 2—2, 50 of Fig. 1.

Fig. 3 is a detail in section of the valve illustrating the adjusting means and mounting therefor.

Figs. 4, 5, 6 and 7 are sectional views illustrating the position of the parts at different periods in the cycle of operation.

It will be understood that I have shown my invention in its preferred form, and in that form, 1 indicates the wall of a cylinder having at one end what I may term the 60 working or combustion chamber 2 and at the other end what I may term a pumping chamber 3, the latter being of larger diameter than the diameter of the working chamber. 4 represents the wall of the working chamber, the same being spaced from the outer wall of the cylinder to form the usual water jacket. The piston comprises a working portion 5 which reciprocates in the working chamber 2, and a pumping portion 6 which 65 reciprocates in the pumping chamber 3. The piston may be connected in the usual way by the rod 7 to a crank 8 on the engine shaft 9. 10 is a fly-wheel. 12 is the bottom of the crank casing which casing is preferably 70 open to atmosphere whereby ready access may be had at all times to the crank and associated parts. 13—13 are the usual webs and supporting lugs on the upper part of the crank case by which the engine may be 75 mounted on a suitable base or bed. 14 represents an opening in the head of the cylinder 1 for the reception of a suitable ignition device such as a spark plug 15. 16 is an exhaust port leading from the side of the 80 cylinder near the lower end of the working chamber, and so positioned relatively to the working end 5 of the piston that the latter will uncover and open said port at the end of the power stroke, and whereby said port 85 will be closed by the working end 5 of the piston at the beginning of the compression stroke. 17 indicates a fuel supply pipe which may be led to the engine from a carburetor or any suitable fuel supplying 90 device, not shown. 18 is an inlet port opening into the working chamber 2 at the opposite end from the exhaust port 16. 19 represents a rotary valve mounted in a cylindrical valve casing 20 and operating to open 95 and close the various ports at the proper time, as hereinafter described. In the preferred form of construction, the valve 19 is carried by a supporting shaft 20 mounted at its ends on bearings 21, which latter are 100 carried by adjustable studs 22, screw threaded at 23 into the wall or frame of the engine. The screw threaded studs 22 may be provided with heads 24 and lock nuts 25 for facilitating proper adjustment and fixing said 105 parts in definite adjustment. By this or equivalent means, the valve 19 may be ad-

justed to the proper position relatively to its seat in the valve casing 26, and particularly with reference to the inlet port 18 so that it may effectively close the same during the power stroke of the piston. Again, by this arrangement wear will come on the bearings or the shaft 20 rather than upon the face of the valve thus increasing its durability and lessening the necessity for frequent adjustment. The valve casing 26 in addition to having communication with the working chamber 2 through the port 18 and with the fuel supply pipe 17 is also in communication with a passage 29 which leads from the pumping chamber 3 of the cylinder upwardly to the valve chamber 26. Communication between the interior of the valve casing 26 is effected preferably by two ports 27, 28 which are respectively diametrically opposite the fuel supply port 17 and the inlet port 18. The passage-way 29 is preferably formed between the shell of the cylinder 1 and a supplemental outer wall 30. The valve 19 has a transverse passage or cross-port 31 which extends diametrically therethrough and which is adapted for one period to connect the fuel passage 17 with the port 27, and for another period to connect the port 28 with the inlet port 18, the said cross-port 31 being closed for certain intervals between said periods.

This rotary valve in its preferred form is driven at one-half engine speed, any suitable means being provided to rotate said valve. In the specific form shown in Fig. 2 the outer end of the shaft 20 which carries the valve is provided with a spiral gear 32 meshing with a similar gear 33 on a shaft 34 which has a corresponding spiral gear at its lower end meshing with a spiral gear 35 on the engine shaft. It should be understood that the depth of the gear teeth on the gears 32 and 33 will be sufficient to permit of such an adjustment of the shaft in its bearing as may be required for the proper working of the valve, which adjustment is very slight.

Operation: The cycle of operation may be clearly understood by referring to Figs. 4 to 7 inclusive. In Fig. 4 it should be understood that the piston is part-way down on its power stroke. The valve 19 is in a position to open communication between the fuel pipe 17 and the passage 29, hence, fuel is being drawn into the pumping chamber 3 at this time. When the piston has reached the end of its forward stroke (see Fig. 5) it has uncovered the exhaust port 16 so that the burnt gases may at such time freely escape. At this time the valve 19 has cut off communication between the pump chamber 3 and the fuel supply pipe 17. At this time the valve also continues to close the inlet port 18. On the return stroke of the piston, as soon as the working end 5 has moved up

sufficiently to close the exhaust port 16 (see Fig. 6), the valve 19 will have turned sufficiently to begin to open the inlet port 18 and the port 28, so that during the balance of the return stroke the combustible mixture contained within the pumping chamber 3 and the passage 29 will be forced into the working chamber 2 against the return movement of the piston. The capacity of the pumping cylinder 3 should preferably be in excess of the displacement of the working end 5 of the piston, so that a charge of gas in volume at least equal to the displacement of said piston end 5 will be introduced into the working chamber 2. The introduction of this gas continues throughout nearly the entire compression stroke of the piston, but is preferably checked by the valve 19 just before the piston reaches the end of its compression stroke. For example, the cutting off of fuel to the chamber 2 may occur when the piston reaches approximately the position on its compression stroke indicated in solid lines in Fig. 7. The balance of the compression stroke which carries the piston up to approximately the dotted line position still further compresses the gas in the working chamber so that it may be properly ignited to cause the piston to move ahead on its power stroke. In Fig. 95 the valve 19 is shown in approximately the position it will assume when the piston end 5 has moved forward slightly on its power stroke, at which moment the crossport 31 starts to open the passages 17-29 so that a new charge of gas may be drawn into the pumping chamber 3 to be delivered to the working chamber on the next up or compression stroke of the piston. The dotted line position of the valve shown in Fig. 7 indicates approximately the position of the port when the piston is at the extreme top dead center position.

I have shown the invention embodied in a single cylinder engine, but it is obvious that the relative number of cylinders may be multiplied as desired. It is also obvious that I may make other changes and modifications without departing from the spirit or scope of the invention.

I claim:

1. In a two-cycle engine in combination, a cylinder having a working chamber with an inlet port at one end and an exhaust port at the other end, a piston arranged to reciprocate therein and controlling the exhaust port to open the same at the end of its working stroke, means for introducing an ignitable charge in said working chamber throughout substantially the entire compression stroke of the piston therein, said means comprising a pump cylinder of larger internal diameter than the working chamber, said piston having a pumping end working in said pumping chamber, a passage from said

- pumping chamber to said inlet in the working chamber, and a valve in said passage operable to open and close the same, said valve operating to open said passage
- 5 throughout substantially the entire compression stroke of said piston, said valve closing said passage during the exhausting period and during the last part of the compression stroke.
- 10 2. In a two-cycle engine, a fuel supply pipe, a cylinder having a working chamber and a pumping chamber, a piston having a working end and a pumping end adapted respectively to said chambers, a single rotary valve having a port diametrically therethrough, with means for rotating the same at half the speed of the engine for controlling communication both between said pumping chamber and said fuel supply pipe, and between said pumping chamber and said working chamber.
- 15 3. In a two-cycle engine in combination, a fuel supply pipe, a cylinder providing a working chamber and a pumping chamber, a valve chamber having ports communicating with the fuel supply pipe and with said working chamber and with said pumping chamber, a rotary valve having a cross-port therein for controlling communication between the pump chamber and the fuel supply pipe and between the pump chamber and the working chamber, with means for rotating said valve in one direction at one-half the engine speed.
- 20 4. In a two-cycle engine in combination, a fuel supply pipe, a cylinder having a pumping chamber, and a working chamber with an exhaust port at one end thereof, and an inlet port at the opposite end, a piston adapted to said chambers, a valve having a passage therethrough and having a turning movement for opening communication between said fuel supply pipe and said pumping chamber during substantially the entire
- 25 working stroke of said piston and for open-
- ing communication between said pumping chamber and said working chamber during substantially the entire compression stroke of said piston.
5. In a two-cycle internal combustion engine, a cylinder having a working chamber of one diameter and a pump chamber of a larger diameter, a piston having a working end and a pumping end adapted respectively to said chambers, a cylindrical valve chamber, a passage leading from the pumping chamber to the wall of the valve chamber, the interior of said passage being in communication with the interior of said valve chamber, two ports in the wall of said valve chamber, one of said ports affording an inlet into said working chamber adjacent to the cylinder head, the other port communicating with a source of fuel supply, a valve having a cross-port, said valve being rotatably mounted in said valve chamber and operable to alternately open communication between said passage and the last two mentioned ports, means for rotating said valve, an exhaust port in the side of the working chamber at the opposite end from the inlet port and arranged to be opened and closed by the working end of said piston, the wall of said valve chamber serving to close said cross-port at timed intervals during the rotation of said valve, said cross-port operating to afford communication between the pumping chamber and the working chamber throughout substantially the full compression stroke of said piston and then only to open said passage to the fuel supply port throughout substantially the full power stroke of said piston and while said exhaust port is open.
